UNITED STATES PATENT OFFICE

2,091,405

MINING MACHINE

Robert K. Jeffrey, Bexley, and Lewis E. Mitchell,
Columbus, Ohio, assignors to The Jeffrey
Manufacturing Company, a corporation of
Ohio

Application March 17, 1934, Serial No. 716,160

18 Claims. (Cl. 262—30)

Our invention relates to low vein, longwall, bottom kerf-cutting machines comprising a pivoted cutter bar adapting it to be used for either short-wall operations or longwall operations, and one of the objects of our invention is the provision of improved and simplified construction in this type of mining machine.

Another object of the invention is the provision in a kerf-cutting mining machine which slides on its own bottom over a mine bottom during operation, of improved mechanism to enable operation of such a mining machine on steep pitches more reliably and with a greater degree of safety.

A further object of the invention is the provision in a coal mining machine of an additional haulage device primarily for safety purposes so that if the main haulage mechanism becomes inoperative the additional haulage mechanism will act to hold the mining machine safely in desired position.

Another object of the invention is the provision of main haulage mechanism for a coal mining machine combined with an auxiliary haulage mechanism which may be relied on as a safety device in the event that the main haulage mechanism becomes inoperative, both or either of said haulage mechanisms being available under various conditions for the purpose of effecting feeding of the coal mining machine during operation either by the longwall method or the shortwall method.

Another object of the invention is the provision of improved and simplified feeding mechanism for a flexible draft element having its free end anchored in the mine extraneous to the machine.

A further object of the invention is the provision of mechanism for operating a rope drum either at a slow feeding speed or at a relatively fast hauling speed from the same source of power and in one direction only by preventing rotation of the rope drum in the opposite direction from such source of power thereby enabling the rope drum to wind up but preventing it from paying out by power.

Another object of the invention is the provision of feeding and hauling mechanism for a coal mining machine operated from a source of power and embodying an improved clutch which will prevent reversal of the haulage mechanism and always maintain operation of the feeding mechanism in the same direction.

Another object of the invention is to provide for a rope drum in a coal mining machine a clutch controlled by a device which shall remain sta-

tionary during the rotation of the rope drum by power.

Further objects of the invention will appear hereinafter, the novel features and combinations being set forth in the appended claims.

In the accompanying drawings,

Fig. 1 represents a plan view of the mining machine embodying our improvements;

Fig. 1^a is a section on the line 1^a—1^a of Fig. 1;

Fig. 2 is an elevational view of the mining machine shown in Fig. 1;

Fig. 3 is an enlarged plan view of the cutting end of the machine with certain parts removed and others shown in section to facilitate illustration of controlling and operating mechanism;

Fig. 4 is a sectional elevational view approximately on the line 4—4 of Fig. 1 looking in the direction of the arrows;

Fig. 5 is a sectional elevational view taken on the line 5—5 of Fig. 3 looking in the direction of the arrows;

Fig. 6 is an enlarged plan view with certain parts removed and others shown in section, of the haulage or front end of the machine shown at the right hand end of Fig. 1;

Fig. 6^a is a view taken on the line 6^a—6^a of Fig. 6;

Fig. 7 is a sectional elevation taken on the line 7—7 of Fig. 6 looking in the direction of the arrows;

Fig. 7^a is a view taken on the line 7^a—7^a of Fig. 7, looking in the direction of the arrows.

Fig. 8 is a sectional plan view taken on the line 8—8 of Fig. 7;

Fig. 9 is a sectional plan view of the auxiliary rope drum and the safety devices associated therewith;

Fig. 10 is a sectional elevational view of a portion of Fig. 9 taken on the line 10—10 looking in the direction of the arrows;

Fig. 11 is an enlarged detailed view of a portion of Fig. 10;

Fig. 12 is an elevational view of the interior structure shown in section at the right hand portion of Fig. 7, the section being taken on line 12—12 of Fig. 6 looking in the direction of the arrows;

Fig. 13 is a sectional elevation taken on the section line 13 of Fig. 6 looking in the direction of the arrows, Fig. 13 being in elevation similar to Fig. 12 but omitting certain parts and adding others;

Fig. 14 is a sectional plan view taken on the line 14—14 of Fig. 13;

Fig. 15 is an enlarged sectional elevation taken

on the line 15—15 of Fig. 6 looking in the direction of the arrows;

Fig. 16 is a sectional elevation taken on the line 16—16 of Fig. 15 looking in the direction of the arrows; parts being broken away to show other parts;

Fig. 17 is an elevational view of one of the skids connected to the bottom of the mining machine;

10 Fig. 18 is an enlarged view of the means for detachably connecting one end of each of the skids to the bottom of the mining machine;

Fig. 19 is an enlarged sectional elevation of the hydraulic jack connected to the right hand 15 end of the skid as viewed in Fig. 17;

Fig. 20 is a sectional elevation taken on the line 20—20 of Fig. 3 looking in the direction of the arrows, and showing the pump mechanism for the hydraulic jacks connected to the skids;

20 Fig. 21 is a diagrammatic view of the fluid pressure control system for the hydraulic jacks associated with the skids one of which is shown in elevation in Fig. 17;

Fig. 22 is a sectional view of the controlling 25 valve of the system shown in Fig. 21;

Fig. 23 is an enlarged elevational view of a portion of the mechanism for operating the clutch for connecting the motor operated power transmission mechanism to the chain cutter; 30 view taken on line 23—23 of Fig. 3;

Fig. 24 is an enlarged sectional plan view of a portion of the mechanism for operating the motor controller;

Fig. 25 is an enlarged sectional plan view of 35 certain details of construction of the mechanism for operating the motor controller;

Fig. 26 is a wiring diagram of the electrical connections between the motor controller and the motor;

40 Fig. 27 is a sectional elevation showing the details of construction of the manually operated mechanism for actuating the motor controller;

Figs. 28, 29 and 30 represent diagrammatically shortwall operations of the improved mining 45 machine;

Fig. 31 represents the arrangement of the ropes when the machine is permitted to slide of its own weight over the mine bottom toward the right;

50 Fig. 32 represents the position of the ropes when the machine is to be moved over the mine bottom by power after having been permitted to slide down an incline;

Fig. 33 represents the position of the haulage 55 ropes when the machine is to be moved to a working face preparatory to a cutting operation;

Figs. 34 and 35 represent longwall operations in opposite directions;

Fig. 36 represents a swinging kerf cutting 60 movement into a longwall face;

Figs. 37, 38 and 39 represent diagrammatically the completion of a longwall cut at the end of a longwall face; and

65 Figs. 40 and 41 represent diagrammatically the haulage of the mining machine from its position where it has completed a longwall cut.

By referring to Figs. 1 and 2, it will be seen 70 that the supporting framework of the mining machine comprises an intermediate motor section 43, a front feeding and hauling section 44, and a rear cutting section 45. These sections are detachably connected together by means of stud screws as illustrated at 44' and 45' in Figs. 3 and 6. An elongated kerf cutter 46 projects 75 from the rear end of the cutter-head section 45

and is pivotally connected thereto. Releasable locking mechanism comprising vertical pins 47, 47 is relied on to hold the kerf cutter in the position shown in Fig. 1 during the shortwall operations illustrated in Figs. 28, 29 and 30, or to hold the kerf cutter in laterally projecting positions for longwall operations illustrated in Figs. 34 to 39 inclusive. The elongated kerf cutter 46 comprises elongated cutter bar 48 with a chain cutter 49 arranged to travel on the periphery thereof. The feeding and haulage section 44 comprises flexible draft elements which may be ropes as shown at 50 and 51 in Fig. 1, the free ends of which are adapted to be connected to fixed anchorages extraneous to the machine as 15 illustrated in Figs. 28 to 41 inclusive.

Each of the sections 43, 44 and 45 is self-contained and when bolted together the overall height of the machine is no greater than the distance between the horizontal planes extending through 20 the upper and lower surfaces of the motor section 43. The machine is therefore well adapted for the cutting of kerfs in relatively low veins and the construction hereinafter described permits the use of a relative high horse power electric motor and the use of operating and controlling apparatus within the space between such upper and lower horizontal planes while at the same time keeping the width and length of the supporting framework within such limits as is consistent with the free sliding of the machine on 25 its own bottom over the mine bottom along narrow passageways between timbering and the upright coal faces and other places in the mine where the available spaces are very limited.

30 The bolting together of the various sections 43, 44 and 45 is such that the sections may be readily separated at the coal face where the roof in the entry or room is only slightly higher than the top of the machine itself. This is an advantage 40 when repairs and replacements are desired to be made adjacent to the coal face; for instance, the armature and field coils of the electric motor may be replaced and the sections reassembled adjacent to the coal face to place the machine in condition for further operations.

In Fig. 3 the electric motor armature 52 is shown provided with a shaft 53 journaled in the ball bearing 54 and having secured at the right end thereof a pinion 55 which meshes with a 50 gear 56. The latter is keyed to the left hand end of the shaft 57 journaled in the bearings 57' and 57'' mounted in the frame of the cutter-head section 45.

The shaft 57 carries a worm 58 which meshes 55 with a worm wheel 59 rotatable on a vertical axis approximately midway between the sides of the machine. The worm wheel 59 as shown in Fig. 5 is secured to a hub 60 mounted loosely on the bushing 61 which surrounds the vertical shaft 60 62.

The vertical shaft 62 is journaled to rotate between the top conical thrust bearing 63 and the bottom conical thrust bearing 64 between the cover plate 65 and the bottom casting 69 of the 65 box-like enclosure having the end wall plates 67 and 68.

As shown in Fig. 1 the cover plate 65 may be secured by means of bolts 69 to the vertical wall plates of the box-like enclosure shown in Fig. 5. 70

By means of a transverse partition 71 the interior chamber 71 is provided for containing lubricating oil which may be introduced through the opening at 72.

An auxiliary cover plate 73 is detachably se- 75

cured by means of the cap screws 74 to the ring shaped support 75 which depends from the cover plate 65 and may be integral therewith as shown in Fig. 5. The inner surface of the support 75 is cylindrical to receive the outer roller bearing race 76, the inner race 77 being secured to the upper end of the shaft 62. A cap plate 78 kept from rotating relatively to the shaft 62 by means of the pin 79, may be secured in place by means 10 of the screw 80 as shown in Fig. 5 so as to hold the inner race 77 in place.

When the auxiliary cover plate 73 is removed the chamber 81 may be filled with lubricant for the upper thrust roller bearing. The worm gear 58, 59 and the parts below the same may be lubricated by introducing lubricant through the oil opening 72 in the main cover plate as shown in Fig. 5. Preferably the oil introduced into the chamber 71 should be at such a level as to 20 submerge only the lower portion of the gear 59 so that when the machine is on steep grades the oil in chamber 71 will not drain over into the hydraulic pump compartment hereinafter described.

25 Intermediate the ends of the shaft 62 is welded, as indicated at 82 in Fig. 5, a cup shaped support 83 which carries on its outer surface a plurality of circumferentially spaced vertical splines 84 which drive the vertically slidable 30 clutch element 85. The lower portion 86 of the clutch element 85 is cylindrical in shape and provided with an annular shoulder 87 against which is held the clutch lifting ring or yoke 89. A series of circumferential oblong openings 81 35 is provided to reduce the weight of metal, as clearly shown in Figs. 3 and 5. The yoke 89 is held in place by means of a collar 88 secured to the lower end of the member 86 by means of shoulder pins. The movement of the clutch yoke 40 89 up or down carries the clutch element 85 into or out of engagement with the clutch element 94. It should be understood that when the cover plate 65 is removed the worm gear 59 and the cup shaped support 83 may be removed and then 45 when the shoulder pins are released the lower clutch element 85 may be also released from the yoke 89.

Riveted to the under side of the hub 60 as indicated at 92 is a ring 93 the under side of which 50 is provided with a series of clutch teeth 94. It should be understood that the hub 60 always rotates with the worm gear 59 and that the cup shaped support 83 always rotates with the vertical shaft 62. The upper side of the clutch element 85 is provided with clutch teeth adapted to engage the upper clutch teeth 94.

At diametrically opposite sides of the disc shaped yoke 89, 90 are trunnions 95, 95 to which are journaled the arms 96, 96 pivoted at 97, 97 to brackets the lower ends of which are screw-threaded at 98, 98 to the bottom 99 of the box-like enclosure.

The bottom 99 of the cutter-head section 45 is provided with a recess at 100 for the lower roller bearing 64 and immediately above this recess but of larger diameter is another recess 101 to receive the means comprising the cork ring 102 for providing an oil seal to prevent loss of lubricant from the bottom of the chamber 71. The oil seal at 103 55 below the roller bearing 64 and immediately above the chain driving sprocket 104 is provided for the purpose of preventing dirt or foreign matter from entering the lower side of the roller bearing 64.

It will thus be seen that all of the bearings in 75 the cutter-head section 45 are well lubricated, the

gear drives being placed in an oil-tight gear housing which has a removable top cover plate 65 so that the gears may become readily accessible for replacement or repairs.

Although the chain driving sprocket 104 is 5 shown riveted at 105 one of the rivet heads may be removed and the rivet detached so that when the sprocket 104 is removed the shaft 62 together with the hub 60 and worm gear 59 may be taken out of the housing after the cover 65 has been 10 detached. When the shaft 62 is lifted out, the inner race of the lower roller bearing and the cup shaped support 83 may be also removed. On account of the curvature of the teeth of the worm gear 59 the caps for the ball bearings 57 and 57 shown in Fig. 3 should first be detached 15 so as to free the worm 58 from such curvature. When the worm gear 59 is lifted out, the lower clutch element 85 remains connected to the clutch yoke 89. The pins holding the collar 88 in place cannot be withdrawn until the cup-shaped support 83 has been lifted out of the clutch element 85. The pins may then be pressed inwardly to release the collar 88, whereupon the clutch element 85 may be removed. 20

The kerf cutter 46 shown in Figs. 1 and 2 comprises a cutter bar 48 which is so supported on the cutter-head section 45 that the lower plane of the kerf cut by the kerf cutter will be flush or substantially flush with the bottom of the machine. That is to say, the lower plane of the kerf to be cut should be in continuation of the plane of the mine bottom. 25

The cutter head has the form of a circular turntable 107 which is provided with an overhanging bracket 108 to which the cutter bar support 48' is rigidly secured by any desirable securing means such as the welding 107' shown in Fig. 5. 30

As shown in Figs. 4 and 5 the lower surface 109 of the wearing shoe 108' which is secured to 40 the cutter-bar support 48' by the cap screws 106, is adapted to slide over the mine bottom during cutting operations. It should be understood that when the cutter bar support 48' is mounted as shown in Fig. 5 it is rigidly connected to the turntable 107 to extend radially therefrom and rotate 45 bodily therewith.

The central portion of the turntable 107 is provided with a cylindrical hub 110 which is journaled on the outer cylindrical surface of 50 the depending cup shaped portion 66 of the bottom casting 99.

A circular plate 111 is welded to the bottom of the casting 99 to form part of the annular groove 112 into which are fitted two semi-circular plates 55 113. By means of a series of circumferentially spaced screws 114 the semi-circular plates 113 are rigidly attached to the upper peripheral circular portion of the turntable 107. The turntable is thus suspended from the bottom of the casting 60 99 by means of the semi-circular plates 113 fitting in the groove 112.

When it is desired to remove the cutter head or rotatable turntable 107 together with the cutter bar rigidly attached thereto, the screws 114 may be removed to release the semi-circular plates 113. Some of the screws 114 may be released by removing the screw plug 115 shown at the left hand portion of Fig. 5. This may be done after removing the cover plate 116 which is detachably mounted as shown in Fig. 1 by means of the bolts or screws 117. The removal of the cover plate 116 also renders accessible the mechanism located in the compartments containing the pump- 75

ing apparatus and the inter-meshing gears 55 and 56.

The mechanism for applying and releasing the clutch shown in Fig. 5 for connecting the worm wheel 59 to the chain driving sprocket 104, is operable from the front end of the machine where the haulage and feeding section 45 is located. As shown in Fig. 3 a cross-piece 118 connects the ends of the arms 96 remote from the trunnions 95. At the center of the cross-piece 118 is an arm 119 to which is screw-threaded a pivot block 120 as shown in Fig. 23.

A stationary bracket 121 is mounted on a support 122 which is secured to the bottom wall 93 of the chamber 71 as indicated at 122' in Fig. 23. Toggle mechanism comprising the links 123, 124 and 125 is connected between the pivot block 120 and the upper end of the bracket 121. When the link 125 is pulled toward the left as viewed in Fig. 23 the pivot block 120 is pushed down and therefore the trunnions 95 shown in Fig. 3 are lifted and this operation effects throwing in of the clutch comprising the elements 85 and 94.

The left hand end of the link 125 is pivoted 25 at 129 to the link 130 the lower end of which is pivoted at 131 to the bracket 122, and the upper end of which is pivoted at 132 to the pivot block 133 into which is screw-threaded an operating rod 134. The forward end of the operating 30 rod 134 is mounted in a slide bearing 135 as shown in Fig. 24 and the end of the rod is provided with a cross-piece or hub 136 which engages the front face of the bearing 135 so as to limit the movement of the rod 134 rearwardly 35 or toward the right as viewed in Fig. 24. The cross-pin 136 supports the handle 137 which may be lifted to a horizontal position as shown in dotted lines at 137' in Fig. 24 and then grasped to pull the rod 134 and thereby move the link 40 125 to the left as viewed in Fig. 23. The pulling out of the handle 137 pushes down the arm 119 shown in Fig. 3 and consequently the trunnions 95 are lifted and the clutch is applied to connect the worm gear 59 to the vertical shaft 45 62 and the chain driving sprocket 104. A coil spring 126 is supported on studs 127 and 128 on bracket 121 and link 130, respectively.

The spring 126 is a compression spring and therefore assists in applying the clutch but the 50 pivot 138 does not move into a straight line extending through the pivots 139 and 140 but remains to the right thereof as viewed in Fig. 23.

The spring and the toggle mechanism are therefore able to easily hold the clutch applied 55 when the handle 137 is released. When it is desired to release the clutch the rod 134 must be pushed back to its full line position shown in Fig. 24 and this operation will effect a positive movement of the link 125 to its position shown 60 in Fig. 23 whereupon the arm 119 shown in Fig. 3 will be positively lifted and the clutch elements 85 and 93, 94 will be released by a direct force exerted by the attendant when he grasps the handle 136 and pushes the rod 134 rearwardly back to its position shown in Fig. 24. It will thus be seen that the spring 126 in its 65 tendency to apply the clutch counterbalances the weight of the clutch element 85 and the ring 89 tending to release the clutch, thereby greatly 70 facilitating the manual operation of the clutch in applying and releasing the same.

Referring now to the haulage and feeding section 44 of the machine, it will be seen that the forward end of the armature shaft of the electric motor 52 is coupled to a shaft 141 journaled

in ballbearings and secured to the worm 142 which meshes with a worm wheel 143 journaled on the vertical shaft 144. By means of three bolts 145 an eccentric cam 146 is rigidly secured to the hub portion 147 of the worm gear 143. The worm gear 143 and the eccentric cam 146 are respectively mounted on spaced ballbearings 148 and 149 for free rotation relatively to the vertical shaft 144. When the motor operates to rotate the worm 142 rotary motion is imparted through the worm gear 143 to the eccentric cam 146 to rotate the latter freely on the ball-bearings 148, 149 relatively to the vertical shaft 144.

When the eccentric cam 146 rotates it engages 15 a circular ring 150 which is mounted by means of the roller bearings 151 for free rotation on the vertical bearing 152, as shown in Figs. 6 and 7.

The ring roller 150 and the vertical bearing 152 are carried on the bell crank lever 153 as shown in Fig. 6. This bell crank lever is pivoted at 154 where it is supported by the frame 155 for oscillation on a fixed vertical axis.

To that end of the bell crank lever 153 remote from its pivot 154, is pivoted at 156 a screw rod 157 which is adjustably connected to the screw-threaded block 158, the latter being pivoted at 159 to the oscillating pawl carrier 160.

By referring to Fig. 7, it will be seen that the pawl carrier 160 is provided with a central circular portion which is journaled on the hub 161 of the ratchet wheel 162, the latter being keyed as indicated at 163 to the upper end portion of the vertical shaft 144. The pawl carrier 160 may be locked in place as shown in Fig. 7 by means of the cylindrical bracket 164 suspended from the bottom of the plate 165 which is secured by bolts 167 to the box-like structure comprising the vertical plates 168.

The cover plate 166 may be fastened to the plate 165 by the machine screws 166', there being apertures in the plate 166 that may fit over the heads of bolts 167 as shown in Fig. 1.

A central circular cover plate 169 may be connected by means of the screws 170 as shown in Fig. 1, to the central portion of the plate 165. When the plate 169 is removed access may be had to the chamber 171 to lubricate the ball bearings 172 which fit in the cylindrical recess in 50 the bracket 164. The ball bearings 172 afford a means of journaling the upper end of the vertical shaft 144 in the bracket 164.

When the cover plate 165 is removed access 55 may be had to the chamber 173 and the mechanism therein. It should be understood that the chamber 173, when all the parts are assembled and when the covers are attached, affords a closed lubricating chamber for the worm gearing and the ratchet feeding mechanism, all of the parts 60 shown in Fig. 7 in the chamber 173 running in oil.

Pivoted at 174 to the pawl carrier 160 is a spring 65 pressed pawl 175 in position to engage the teeth of the ratchet wheel 162. It will thus be seen that when the cam 146 is rotated, the bell crank lever 153 will be oscillated and the pawl and ratchet mechanism will be intermittently actuated to effect a step by step feeding movement of the vertical shaft 144 in an anti-clockwise direction as viewed in Fig. 6. A spring pressed 70 retaining pawl 176 is pivotally mounted on the axis 154 for movement independently of the bell crank lever 153 and in position to engage the ratchet teeth to prevent retrograde movement of the vertical shaft 144. By means of the ad- 75

justment which may be effected between the members 157 and 158 the pawl 175 may be adjusted so as to enter properly the notch between the ratchet teeth when the roller 150 is nearest the vertical shaft 144.

The rotation of the cam 146 thrusts the roller 150 outwardly away from the shaft 144 and thereby causes a forward anti-clockwise movement of the pawl 175 together with the ratchet wheel 162. In order to return the pawl 175 to its initial position a restoring spring shown at 177 in Figs. 6 and 15 is relied upon. This spring is located in the tube 178 between the transverse partition 179 and the head 180 which is pivotally connected at 181 to the link 182 the other end of which is pivoted at 183 to the bell crank lever 153. (See Fig. 15.)

The restoring movement or return throw of the pawl 175 may be varied or regulated in accordance with the extent of feed desired. A rod 184 which is pivotally connected at one end to the head 180, slides through the center of the partition 179 and is connected at its outer end to the stop 185. It will thus be seen that the spring 177 can move the pawl 175 in a clockwise direction as viewed in Fig. 6 only to the extent permitted by the stop 185 striking against the partition 179.

The position of the partition 179 may be varied by sliding the tube 178 in the cylindrical or tubular support 183 which is detachably secured to the plate 187, the latter being in turn detachably secured to the supporting framework of the machine.

55 Mounted in the cap bearing 188 is an adjusting screw 189 capable of rotary but not endwise movement (Fig. 15). When the manually operable wheel 190 is rotated the screw 189 is rotated and since this screw is screw-threaded through 40 the left hand end of the tube 178, as viewed in Fig. 6, the partition 179 will be moved to varied distances from the shaft 144.

As shown in Figs. 6, 15 and 16 a collar 191 fits in the cap bearing 188 for rotary movement and 45 is provided with a notch 192 in which is adapted to fit a ball 193 urged by the spring pressed cup 194 into the notch. The compression of the spring 195 may be regulated by the screw plug 196.

50 The pitch of the screw-threads 189 is such that when the wheel 190 is given one rotation so that the ball 193 may be reseated in the notch 192 the partition 179 will be moved such a distance as to cause the pawl 175 to be reset to a position one notch from its previously adjusted position. For instance, the adjustment of the partition 179 may be such as to cause the pawl 175 to remain in a certain notch even though the cam 146 is rotated, thereby effecting no feed at all. Adjustments may also be made to cause the pawl 175 to move the ratchet wheel either one notch, two notches, three notches or four notches, as may be desired. Full speed feeding transmission mechanism may thus be effected for purposes hereinafter more fully explained. It should be particularly noted, however, that all feeding movements or step by step advances of the ratchet wheel 162 are uni-directional irrespective of the direction of rotation of the armature shaft. That 65 is to say, it is immaterial whether the motor is rotating in one direction or in a reverse direction. The rotation of the cam 146 will always cause oscillation of the bell crank 153 so that the reciprocation of the pawl 175 will always be the same 70 and the rotation of the shaft 144 as viewed in

Fig. 6 will always be in an anti-clockwise direction.

At the lower end of the vertical shaft 144 as shown in Fig. 7 is a pinion 197 which meshes with a gear 198 journaled by means of the ball-bearings 199 to the vertical bearing 200 extending upwardly from the bottom plate 201 of the supporting frame of the haulage and feeding section 44. The gear 198 meshes with the relatively larger gear 202 which is keyed at 203 to the cylindrical hub 204 to the upper end of which is connected one element 205 of a friction clutch 206, the other element 207 of which is located on the interior of the rope drum 208. The bushing 209 is pressed into the sleeve 204 for journaling on the vertical stationary bearing 210, the latter being secured to the top plate 234 by being keyed thereto as shown in Fig. 7.

As shown in Fig. 8 the gear 202 meshes with a gear 211 mounted to rotate about vertical bearing 212 which is similar to the vertical bearing 210. Also mounted to rotate about the vertical axis of the bearing 212 is a rope drum 213, and between the gear 211 and the rope drum 213 is a sleeve friction clutch and rope drum similar in all respects to the structure shown at the left hand portion of Fig. 7. The gear 202 rotates in an anti-clockwise direction as viewed in plan and the gear 211 rotates in a clockwise direction and the ratio between these gears is such that the gear 211 will rotate approximately ten percent faster than the gear 202 for purposes hereinafter explained.

As shown in Fig. 7 the hub 216 is provided with a cup-shaped bearing 214 which is held against rotation relative to the bottom plate 201 by means of the pin 215. The hub 216 of the large spur gear 202 rests on the bearing plate 214 within the cylindrical flange 217 which affords an oil cup. This hub 216 carries the portion 204 of the clutch element 205. The upper end of the hub 216 is provided with a ring packing 218 which bears against the inner surface of the stationary ring 219 to form a dirt seal, the ring 219 being mounted in a circular opening in the cover plate 220. This cover plate may be provided with the extension 221 for the space in which the spur gear 211 rotates. A vertical extension may also be provided at 222 (Fig. 7) and suitable partitions provided as shown at 223, 224 and 225 to cooperate with the cover plate 220, 221 to provide an enclosure for the spur gearing shown in 50 plan in Fig. 8.

A star-shaped plate 226 (Figs. 7 and 7a) is connected by means of the pins 226' to the hub 216 to rotate therewith and to make a close sliding fit with the upper surface of the cover plate 220. 55 The star plate 226 acts to throw out coal dust or foreign material from under the rope drum 208 to keep such material from entering the chamber below the plate 220 and to prevent such material from retarding free rotation of the rope drum 208. A similar star plate is located under drum 213.

By providing a floor 227 for the chamber 173 as shown in Fig. 7, a separate closed chamber 228 may be provided for the spur gearing. The central portion of the floor plate 227 may also afford support for the outer race of the ball bearing 230. Suitable lubricating means may be provided for the spur gearing in the closed chamber 228.

Connected to and wound on the rope drum 70 208 is a rope 50 the free end of which is adapted to be connected to a fixed anchorage in the mine extraneous to the machine as illustrated in the diagrammatic views, Figs. 28 to 41 inclusive. Connected to and wound on the rope drum 213 is 75

a rope 51 the free end of which is also adapted to be connected to a fixed anchorage in the mine. The application of power transmitted from the motor to each rope drum is controlled by the 5 friction clutch associated therewith. As above stated, each of the rope drums 208 and 213 is provided with its own friction clutch and each friction clutch is operated by the mechanism shown in Fig. 7.

- 10 A transverse top plate 234 is securely bolted to the side walls of the frame of the section 44 and the upper ends of the vertical cylindrical bearings 210 and 212 are secured thereto so as to prevent rotation of said vertical bearings relative to the supporting frame of the machine. Beneath the plate 234 and keyed to the stationary bearing 210 at 235 is a screw-threaded bushing 236 which is provided in its lower inner side with a seat 237 for a ball bearing 238. It will 15 thus be seen that the sleeve 204 is mounted so that it will have no vertical movement relative to the bearing 210 but may rotate with the bushing 209 while provided with the thrust bearing 238 at its upper end.
- 20 25 Journaled on the bushing 239 surrounding the sleeve 204 is a sleeve-shaped hub 240 at the interior of the rope drum 208. The rope drum is therefore mounted for rotation on the sleeve 204 and the latter in turn is mounted for rotation 30 about the vertical axis of the bearing 210.

35 Mounted at the upper side of the drum 208 as shown at 241 is the outer race 242 of a ball bearing 243 the inner race 244 of which is riveted as shown at 245 to the wheel 246 screw-threaded on 35 to the screw-threaded bushing 239.

40 Radial spokes or handles 247 on the wheel 246, some of which handles always project out from beyond the plate 234, may be used to turn the wheel 246 on the screw 236 to lift or lower the ball bearing 243. This ball bearing supports the rope drum and also the clutch member 207. Therefore, when the ball bearing 243 is lifted the clutch is applied to direct transmission of power from the spur gear 202 to the flexible draft element or 45 rope 50. In a similar manner transmission of power from the spur gear 211 to the rope drum connected thereto may be effected by grasping the radial handles 247' and turning the wheel 246' to obtain a pull on the rope 51. As shown in 50 Fig. 6, when the two rope drums are rotated in opposite directions and each uni-directionally, pulls will be exerted on both of the ropes 50 and 51.

55 As shown in Figs. 1, 2 and 6 rope directional sheaves may be located at various corners of the machine. The directional sheaves may be superimposed as shown at the right hand end of Fig. 2, the wider sheave 232 being used for a rope extending directly from the rope drum, and the 60 upper sheave 233 being used when the rope 50 is directed around the same. One directional sheave 248 is sufficient for the rope drum connected to the larger spur gear 202. These directional sheaves are shown in sectional elevation in 65 Fig. 1^a.

65 At the rear end of the machine a directional sheave 249 may be mounted on an arm 250 which is detachably connected at 251 to a depending bracket 252 or to a depending bracket 252' at 70 either corner on opposite sides of the machine, as shown in Fig. 4.

75 In order to slide the machine over the mine bottom at a relatively fast or haulage speed, mechanism is provided as shown in Figs. 7 and 10 to 14 inclusive, for connecting the worm wheel

143 directly to the shaft 144 and the pinion 197 to drive the latter independently of the pawl and ratchet feeding mechanism shown in Fig. 6. By means of the handle 253 connected to the rock shaft 254 which is journaled in the bearing 255, the slotted disc 256 may be moved from the position shown in Fig. 13 to a clutch applying position and held there after the handle 253 is released.

10 In the slot 257 of the disc 256 is pivoted at 258 the upper end of a rod 259 the lower end of which is provided with a nut 260 engaging the lower end of the compression spring 261, the latter being mounted in a tube 262 the lower end of which is connected to the L-shaped member 263 secured to the arm 264. The other end of the arm 264 as shown in Fig. 14 is secured to a tube 265 journaled on a bearing rod 266 mounted in the brackets 267 and 268. Secured to the other end of the tube 265 is another arm 269. Trunnions 270, 270 carrying a ring 271, are journaled in bearings at 20 the outer ends of the arms 264 and 269 as shown in Fig. 14.

25 Carried by the ring 271 is a lower clutch element 272 which is provided with beveled clutch teeth 272' adapted to engage the upper clutch element 273 secured to the lower side of the worm gear 143 as shown in Figs. 7 and 13. The lower clutch element 272 is disc-shaped and its periphery fits in an inner annular groove of the ring 271. The latter may be constructed of semi-circular parts bolted together as shown at 274, 274 in Fig. 14 to clamp the ring 271 to the clutch element 272.

30 It should be particularly noted that the interior meshing teeth 272' and 273' are provided with such beveled surfaces that when the worm gear 143 is rotated in a clockwise direction as viewed in plan, the clutch 272, 273 will be ineffective to transmit power from the motor to the pinion 197. While it is immaterial whether the motor rotates in one direction or the other when the 35 pawl and ratchet feeding mechanism is to be operated, the worm gear 143 should be rotated only in an anti-clockwise direction when the clutch is applied because such application of the clutch will effect rotation of the ratchet wheel 162 which is 40 keyed to the upper end of the shaft 144 as shown in Fig. 7. The pawl 175 remains in engagement with the ratchet wheel 162 and therefore the shaft 144 must be rotated in an anti-clockwise direction when power is applied directly to the 45 pinion 197. Therefore, when the clutch 272, 273' is applied the motor must be rotated in the proper direction to secure anti-clockwise rotation of the ratchet wheel 162 and the shaft 144. Any 50 attempt to do otherwise would cause the pawl 175 to lock the shaft 144 against rotation whereupon the clutch teeth 272' and 273' will slip relatively to each other even though the pivot pin 258 is held at dead center or beyond, by the spring 261. In other words, when the clutch is applied by 55 means of the handle 253 it will be spring-loaded and the beveling of the clutch teeth will necessitate rotation of the motor in the proper direction to maintain uni-directional rotation of the driving spur gears 202 and 211 for the two rope drums. 60 Consequently, whether the rope drums are rotated by means of the slow speed pawl and ratchet mechanism or by means of the fast speed haulage mechanism the rope drums can be rotated by power only in such directions as to wind up the 65 ropes thereon and can never be operated by power to pay out the ropes. When the ropes are to be paid out the friction clutches may be released to free the drums and the ropes can then be pulled 70 manually for the anchoring of the free ends 75

thereof at predetermined locations in a mine.

An important feature of our invention is the provision of pawl and ratchet mechanism for the rope drum 213 so that the latter may be used as a safety rope drum in the event that the feed rope 50 breaks or its anchorage becomes detached while the machine is being fed upwardly along a steeply pitched mine vein. A circular ratchet 275 is mounted on top of the rope drum 213 in position to be engaged by the pawl 276 which is pivoted at 277 as shown in Fig. 9. This pawl and ratchet mechanism is so arranged that the rope drum 213 may be rotated in a clockwise direction as viewed in plan but will lock the drum against rotation in the opposite direction. Consequently, when the friction clutch of the rope drum 213 is applied and the feed rope 50 should become broken or detached from its anchorage, the weight of the machine can not cause the latter to slide down a steep incline since it will be held from doing so by the applied clutch and the pawl and ratchet mechanism 275, 276.

When the clutch is released and it is desired to pull the rope 51 out from the rope drum 213, the pawl 276 may be released from the ratchet 275 by means of a handle 278 which is secured to the outer end of the pin 279 the inner end of which is connected to the pawl 276 as shown in Fig. 10. A spring 280 surrounds the pin 279 and is located between the top plate 234 and the collar 281 mounted on the stop 282 which extends through the pin 279.

As shown in Fig. 11, a cam plate 283 may be mounted on the upper surface of the top plate 234 and provided with a retaining notch 284 for the handle 278. As indicated by the dotted circles in Fig. 11, the turning of the handle 278 will cause the same to slide up the cam plate 283 into the notch 284 to hold the pawl 276 released from the ratchet 275.

While the principal advantage of the safety rope drum 213 is in longwall operations upwardly along a steep pitch, such safety drum may also be used in various other operations including shortwall operations. Longwall operations upwardly along steep pitches are illustrated in Figs. 34 and 35. The rope 51 is pulled out almost to its entire length and its free end anchored at 285 and the friction clutch for the drum 213 applied to such an extent only as to maintain the rope 51 taut during feeding operations. The feed rope 50 is pulled out a relatively short distance and anchored and the friction clutch of the rope drum 208 applied sufficiently to effect the feeding operation. It should be particularly noted that the feed rope 50 is extended along the coal face on the inner side of the path of travel of the machine whether the operation is being carried on as shown in Fig. 34 or as shown in Fig. 35.

In the shortwall operations illustrated in Figs. 28, 29 and 30 either rope 50 or 51 may be used as the feed rope and the other as the retarding rope. When the shortwall feeding movement is toward the left as indicated in Fig. 28 the friction clutch for the rope drum 213 is applied sufficiently to cause the rope 51 to act as the feed rope while the friction clutch for the rope drum 208 is applied so that it will slip and thereby enable the rope 50 to act as a retarding rope while it is being paid out. In Fig. 29, the rope 50 acts as the feed rope and the rope 51 acts as the retarding rope. In this case the friction clutch is fully applied to the rope drum 208 but the friction clutch for the rope drum 213 is applied so as to permit slipping. In the sumping operation illustrated in

Fig. 30 the friction clutches for the rope drums 208 and 213 are so applied that both of the ropes 50 and 51 will act to feed the machine to produce the sumping kerf illustrated by the dotted lines.

Fig. 31 illustrates the arrangement of the ropes 50 and 51 in letting the machine slide down a steep incline on a mine bottom from the left toward the right. In performing this haulage operation to effect transportation of the machine from one place in the mine to another, the mine bottom may have a rolling formation requiring the use of one of the ropes anchored as illustrated in Fig. 32 wherein the safety rope is still maintained in safety position so that when the machine is moved beyond the roll it will be held against sliding down an incline until the rope 50 can be re-anchored as shown in Fig. 31.

Fig. 33 illustrates the arrangement of the ropes 50 and 51 for haulage of the machine into a corner preparatory for such a sumping operation as that illustrated in Fig. 30. The movement of the machine away from the corner or after the completion of a longwall kerf is illustrated in Fig. 41.

The controller for the electric motor 52 may be mounted in the motor section 43. A longitudinal shaft 288 carries a controller drum as diagrammatically illustrated in Fig. 26, and this controller drum is provided with suitable insulated segments adapted to engage the stationary contacts 289. The shaft 288 as shown in Fig. 24 is arranged to be rocked in order to position properly the controller to effect rotation of the motor at various speeds and in opposite directions. Spiral gearing 290, 291 is mounted on the casting 292 as shown in Fig. 24 to permit a diagonal location of the operating shaft 293. The forward end of the shaft 293 is connected by means of the beveled gearing 294 as shown in Fig. 6 to the vertical shaft 295.

By referring to Fig. 27 it will be seen that the horizontal beveled gear is provided with a sleeve 296 at its center and the upper end of the sleeve 296 is notched at 297 to receive a coupling connection at the bottom of the hub 298 at the inner end of the handle 299. By means of the knob 300 the handle 299 may be lifted so that the latch 301 may move through the semi-circular slot 302, whereupon the coupling between the hub 298 and the sleeve 296 will be released and the latch 301 may ride on the upper surface of the top plate 303. Not until the latch 301 reaches the semi-circular notch 304 can the coupling 298 again become engaged with the sleeve 296.

This construction as shown in Figs. 6 and 27 is for the purpose of compelling the controller to be brought back to its initial position where the current must be cut off from the electric motor, before the motor connections can be reversed. For instance, if the controller handle is moved from neutral position "ahead" until the motor is operating at full speed, the controller handle must be brought back to initial position before the motor can be reversed. This is the reason that the handle is limited to an arcuate movement of less than 180° by reason of the limit stops 305 and 305'.

After the motor has been operated in one direction and brought back to rest by reversing the movement of the handle 299 when occupying the position shown in Fig. 27, the handle 299 may be lifted and the latch 301 moved through the slot 302 and then while the coupling 298 is disengaged from the sleeve 296 the handle may be moved through the slot 304 whereupon the cou-

pling 298 may again be engaged with the sleeve 296 and then, and not until then, can the motor controller be moved in "reverse". This arrangement is desirable because it compels the attendant to take sufficient time to manipulate the handle 299 to permit the motor to come to rest before reversal of the electrical connections can be effected. For instance, if the kerf cutter should bind in the kerf the tendency of the attendant is to effect reversal of the motor as quickly as possible to reverse the direction of travel of the chain and thereby effect release of the kerf cutter in the kerf. Whenever the attendant attempts to reverse the motor quickly he is compelled to operate the reversing switch mechanism in such a manner that the load on the motor will be sufficient to bring it to rest before reversal of the connections can be made.

Referring to the wiring diagram shown in Fig. 26, the developed segments on the shaft 288 may be considered as coming into engagement with the fixed contacts 289 at their left hand ends when the motor is to be operated "ahead" and at their right hand ends when the motor is to be operated in "reverse". When the segments 306 and 307 engage the contacts 308 and 309 the segments 310, 311 and 312 will engage the contacts 313, 314 and 315 respectively. The segment 317 will leave the contact 319. The field coil is shown at 320 and a series winding at 321. The motor armature is shown at 322 and the starting resistance at 323. When the motor is operated in one direction the segments 310 and 312 come into play but when the motor is operated in opposite direction the segments 324 and 325 are used. The high resistance 326 is for the purpose of absorbing the "kicks" from the field coils when the circuits therethrough are broken. Inasmuch as the controlling circuits shown in Fig. 26 are simply for effecting reversal of the motor and the control of the speed thereof further detailed explanation is deemed unnecessary. Sufficient illustration and description are made to show that it is desired to rotate the shaft 288 in one direction for operation of the motor "ahead" and rotating the shaft 288 in the opposite direction for operation of the motor in "reverse". As above explained, these operations can be effected only by moving the handle 299 in a certain direction and bringing it back to initial position and then releasing the handle from the hub 296 and moving it to another notch so that the handle may be re-engaged for movement of the shaft 288 in the proper direction to effect reversal of the electric motor.

Associated with the electric plug 327 for connecting the power terminal 328 to the motor, a plug socket 329 is mounted as shown in Fig. 6. The electric plug 327 can not be withdrawn except when the controller is in off position or when the current is cut off from the motor. A collar 330 is secured to the shaft 293 as shown in Fig. 6a, and is provided with a flattened surface 330' (Fig. 6a) which comes opposite the heel of the locking plate 331 only when the shaft 288 is in such position that the current is cut off from the motor. When the flattened surface 330' is opposite the heel on the locking plate 331, the latter may be swung on its pivot 332 whereupon the electric plug 327 may be disconnected from its socket 329 so as to disconnect the power terminal 328 from the electric motor.

In order that the attendant at the cutter-head end of the machine may effect stopping of the motor whenever desired without being

able to re-start it from that end of the machine, a handle is provided at 333 as shown in Figs. 3 and 4 at the rear end of the pull rod 334 which is connected to mechanism shown in Figs. 24 and 25 for returning the controller drum to neutral position whether the motor is operating in one direction or another. Consequently, in the event of such an emergency as when the kerf-cutter binds in the kerf or the cutting bits strike a "sulphur ball", the emergency motor stop rod 334 may be pulled rearward to cause the chains 335, 336 and 337 to effect movement of the controller drum shaft 288 to such a position as will effect the cutting off of the current from the motor.

As shown in Fig. 25 the forward end of the emergency stop rod 334 is connected to a cup shaped sleeve 338 which is slidably mounted in the tubular support 336. A spring 340 in the sleeve 338 bears against the annular seat 341 at one end and against the head 342 at the other end. The head 342 is connected to a rod 343 and to the other end of the rod 343 the chain 335 is connected. A narrow drum 344 is secured to the controller drum shaft 288 and the chains 336 and 337 are connected to the pins 345 and 346 between the flanges of the drum 344.

When the controller drum is rotated either for "ahead" operation of the motor or for "reverse" operation thereof as diagrammatically illustrated in Fig. 26, the spring 340 will be compressed by movement of either the pin 345 or the pin 346 away from the annular seat 341 but by reason of the friction in the gearing 290, 291 such compression of the spring 340 will not cause the latter to return the controller drum when the actuating handle 299 is released. When the rod 343 as viewed in Fig. 25 is pulled toward the left the ends of the pin 435' carried by the head 342 will slide along the slots 436, 436' in the tube 338 to positions near the left hand ends of such slots. When the emergency rod 334 is pulled toward the right as viewed in Fig. 25 a direct and positive force is exerted between the ends of the pin 435' and the left hand ends of the slots 436', independently of the spring 340. There will therefore be a direct and positive pull exerted on the rod 343 to cause either chain 336 or 337 to rotate the shaft 288 back to its initial position notwithstanding the presence of the gearing 290, 291.

The motor can not be re-started from the cutter-head end of the machine because only by actuating the lever 299 can the controller drum be actuated to re-start the motor in either direction. As shown in Figs. 6 and 27 the operating lever 299 and the connections between the same and the drum shaft 288 are such as to permit pulling of the emergency rod 334 to effect restoration of the controller drum to off position notwithstanding the gearing between the lever 299 and the controller drum shaft 288.

Mounted at the edges of the bottom of the machine so as to extend from the cutter-head section to the feed section, are two independently adjustable skids 347 and 348 each independently operable by means of fluid pressure mechanism controlled from the front end of the machine. Each skid is mounted as shown in Fig. 17 by being adapted to fit into an elongated recess 349 so that when the skid is located in such recess the bottom thereof will be flush with the bottom of the machine. Each skid is detachably connected to the machine so that it may be readily removed for replace-

ment or repair in the event that it becomes bent or worn.

Extending into each of said recesses 349 at the feed section 44 are pins 350 the lower ends 5 of which are provided with diagonal oval shaped heads 351. The skid 348 is provided at one end as shown in Fig. 18 with an elongated or oval shaped slot 352 which is adapted to fit over the head 351 when the skid 348 is located in its 10 dotted line position 348' as shown in Fig. 18. Then when the skid is swung around so as to be immediately below recess 349 it will be locked in position on the pin 350 with sufficient freedom of movement to permit tilting of the 15 supporting framework of the machine as illustrated in Fig. 17.

At the forward central portion of each of the skids 348 is a central vertical pivot block 353 with a transverse hole therein for receiving the 20 pivot pin 354 the ends of which extend through openings in the depending lugs 355, 355 below the plunger 356. The pivot pin 354 may be retained in place by means of cotter pins 357, 357. It will thus be seen that the forward end of each 25 of the skids is detachably connected by means of pivot pins to the lower ends of plungers.

By referring to Fig. 1 it will be seen that the rear end of each of the skids 347, 348 is provided with a hydraulic lifting jack as indicated 30 at 358 and 359. Each of these hydraulic jacks embodies the construction illustrated in Fig. 19. The hydraulic jacks are mounted at the forward corners of the cutter-head section 45.

In Fig. 19 is shown a cylindrical support 360 35 welded at 361 and 362 to the frame of the cutter-head section 45. Extending upwardly into the cylindrical support 360 is a hydraulic cylinder 363 the lower end of which is flanged at 364 to fit into recesses of the framework and held 40 against rotation relatively thereto by the pin 365.

The upper end of the plunger 356 is provided with packing at 366, a packing gland at 367 and a follower at 368, the latter being provided with 45 a cylindrical central portion 369 which is screw-threaded into the recess 370 in the upper end of the plunger 356.

At the center of the follower 368 is an opening 371 concentric with but larger in diameter than 50 the vertical stationary cylindrical rod 372 the upper end of which is screw-threaded at 373 into an opening at the center of the cylinder head 374. The lower end of the rod 372 is provided with an annular flange head 375 which is adapted 55 to enter the cylindrical chamber 376 in the follower 368 and engage the annular shoulder 377. In other words, the head 375 acts as an abutment to limit downward movement of the plunger 356 when hydraulic pressure is exerted in the chamber 378. If desired, openings additional to the 60 annular space 371 may be provided through the follower 368 between the chamber 378 and the chamber 379 so that displacement of the liquid by the rod 372 may be more freely effected 65 when the plunger 356 is moved up or down.

When it is desired to tighten the packing gland 367 or to renew the packing 366, access to the hydraulic jack may be had by disconnecting the skid from the lower end of the plunger 356 and 70 turning the latter while the recess 380 in the top of the follower 368 engages the head 381 projecting downwardly from the bottom of the cylinder head 374. The abutment rod 372 may be removed by applying a screw-driver to the slot 75 382. It can readily be seen that in this manner

the parts may be dis-assembled and reassembled for inspection, repair or replacement.

At 383 in Fig. 19 is shown a screw threaded opening for receiving an L-connection shown at 5 384 in Fig. 21 and such L-connection is connected by pipe 385 to a controlling valve 386 which is shown in section in Fig. 22. In a similar manner the hydraulic jack 359 is connected by an L-connection 387 to the pipe 388 and thence to the controlling valve 386.

As shown in the diagrammatic view of Fig. 21 a vertical reciprocating plunger 389 is operable in a vertical cylinder 390 to draw liquid 10 from the supply tank 391 through the suction port device 392 past the check valve 393. When plunger 389 is moved upwardly the liquid flows to the right through the check valve 393 and when the plunger 389 is moved downwardly the check valve 393 closes and the liquid is forced 15 through the check valve 394 toward the right and thence into the pipe 395. When the pump effects suction the check valve 394 is closed and the check valve 393 is open and when the pump forces the liquid through the pipe 395 check valve 393 is closed and check valve 394 is open.

The valve 396 as shown in Fig. 22 is provided with a port 397 which connects the pipes 395 and 20 385 when in the position shown in full lines in Fig. 22. By moving the valve 396 in a clockwise direction as viewed in Fig. 22 through an angle of 90° the port 397 will connect the pipe 385 25 with the exhaust port 398 so that the weight of the machine may be relied on to force the liquid from the hydraulic cylinder of the jack to the exhaust port 398 and thence back into the supply tank 391.

In a similar manner, the valve 396 may be moved in an anti-clockwise direction through an angle of 90° from position shown in Fig. 22, to effect operation of hydraulic jack 359 when the reciprocating pump is operated. A further turn in an anti-clockwise direction through an angle of 90° will connect the pipe 388 to the exhaust port 398.

The supply tank 391 shown diagrammatically in dotted lines in Fig. 21 may be in the form of 40 a well in a portion of the cutter head section 45 of the machine as shown in Figs. 3 and 20.

In Fig. 20 the pump cylinder 390 is shown detachably but rigidly connected to the supporting framework. At the upper end of the plunger 389 a slotted head 399 fits over a circular terminal 400 at the end of the lower arm of the bell crank lever 401 which is pivoted at 402 to a bracket 403 mounted on a plate 404 which carries the pump cylinder 390. Fitting over the terminal 405 at the upper end of the bell crank lever 401 is a slot 406, in a reciprocating block 407 at the rear end of the pump operating rod 408 which is slidable in the supporting tube 409 mounted in the framework of the motor section 45.

By referring to Figs. 3 and 6, it will be seen that hydraulic pump operating rod 408 extends 50 forwardly into the feed section 44 of the machine, for pivotal connection at 410 to the double arm lever 411 which is pivoted at 412 to the cover plate 234. One arm of the lever 411 is tubular in shape as shown at 413 to receive the valve actuating rod 414. By grasping the handle 415 of the valve actuating rod 414 (when mounted as shown in Fig. 6), the rod 408 may be reciprocated 55 in order to operate the hydraulic pump 389, 390 shown in Fig. 20. In this manner the opera- 60 65 70 75 75

tor at the forward end of the machine may operate either hydraulic plunger independently of the other to effect lifting of the supporting framework of the machine as illustrated in Fig. 17. 5 In this manner, the kerf-cutter including the cutter bar may be lifted up off the bottom of the mine either to adjust the elevation of the kerf cutter for cutting operations or to keep the cutter bar off the bottom of the mine to facilitate 10 haulage of the machine along the mine bottom from one place to another.

Inasmuch as the rod 414 is provided with a socket 416 to fit over the squared head 417 at the forward end of the rock shaft 418, the rod 414 15 with its handle 415 constitutes a socket wrench for operating the valve 396 to its various positions above described in connection with Fig. 22. The rod 414 and its actuating handle 415 constitutes a pump handle when in the position shown in Fig. 20 6 and when its socket 416 is applied to the squared head 417 the rod 414 and its handle 415 constitutes a socket wrench. The rear end of the rod 418 is connected by means of universal joints 419 to the valve 396. It should be understood 25 that the valve port 397 of Fig. 22 may also occupy intermediate positions where the flow of the liquid will be cut off both to and from the pipes 385 and 388 thereby locking the hydraulic jacks connected to the skids, in their adjusted 30 positions.

It will be seen by referring to Figs. 3, 6, 34 and 35, that the hydraulic jacks may be operated during feeding movement of the machine along the coal face while the cutting operation is taking 35 place because the controlling and operating mechanism for the hydraulic jacks is located at the front end or feeding section of the machine where such controlling and operating mechanism is readily accessible to the operator. That 40 is to say, since the squared head 417 of the rock shaft 418 and the oscillating lever 411 are located at the feed section of the machine as shown in Fig. 6, the skids may be adjusted relative to the supporting framework at any time wherever the 45 machine happens to be located, whether very close to the coal face or not. Inasmuch as the cutter bits project upwardly and downwardly above and below the upper and lower surfaces of the cutter bar a kerf is cut of such thickness as 50 to give ample clearance for feeding movement of the cutter bar and such clearance also permits gradual lifting or lowering of the cutter bar by means of the skids during feeding movement of the kerf-cutter. The kerf-cutter may therefore 55 be kept in proper position in the coal vein as the cutting proceeds. Furthermore, when the cutting of the kerf is completed, the cutter bar may be lifted clear of the floor by operation of the controls at the feeding section 44, so that the 60 entire machine may be readily moved to a new cutting position or handled about the floor or mine bottom.

Locking mechanism comprising pins 47 fitting in various holes in the cutter-head may be relied 65 on to lock the cutter bar relative to the framework of the machine either to extend rearwardly as shown in full lines in Fig. 3 parallel to the longitudinal center line of the machine or at various angles relative to the path of travel of the machine along a longwall face. For instance, in Fig. 34 the cutter bar extends approximately 20° relative to a line at right angles to the line of draft of the machine. In Fig. 35 the cutter bar is locked on the other side of the frame 70 75 of the machine at an angle of approximately 20°

relative to a line at right angles to the line of draft. It is preferred to provide two spaced apart vertical locking pins the centers of which are approximately 10° apart as shown in Fig. 3. When the cutter bar is in the full line position shown in Fig. 3 the pin 47 is adapted to fit into an opening immediately below the same in the cutter head 107 in the manner illustrated in Figs. 4 and 5. Similar openings in the turntable are located at the positions 420, 420 as illustrated in Fig. 3, each of these positions being spaced 15° from a line extending through the vertical axis of the sprocket wheel 104 and at right angles to a longitudinally vertical plane extending through the vertical axis of the sprocket wheel 104. It will thus be seen that when the pins 47 and 47' are released the cutter bar 48 may be swung manually or otherwise so that the cutter bar may be locked at 10 or 20° from the transverse line extending through the axis of the sprocket 104 according to whether one or the other of the pins 47 and 47' is inserted in the opening 420. When the pin 47' is in the hole 420 the angle will be 20° and when the pin 47 is in this hole the angle will be 10°. 25

The pins 47 and 47' are mounted in a bracket 421 which is welded to the rear surface of the rear wall 67. The bracket 421 is provided with steps 422 at various heights as shown in Fig. 4 to provide fulcrums for a tool applied to the 30 heads 423, 423 of the locking pins 47 to release the latter from the recesses in the cutter-head 107. Each of the pins is provided with a key as shown at 437, slidably in a vertical keyway 438 so that when the key is lifted and turned the 35 key may hold the pin tip in released position.

When it is desired to effect a swinging feeding movement of the kerf-cutter into the coal face preliminary to a longwall operation as illustrated in Fig. 36, the free end of the safety rope 51 is anchored at 424 and the feed rope 50 is extended around the sheave wheel 232 along the inner side of the supporting framework for connection of an eye at its free end to a hook 425 located on the turntable 107 adjacent either corner of the rear end of the machine when the cutter bar extends rearwardly parallel to the longitudinal center line of the machine. Pockets may be provided as illustrated at 426 in Fig. 2 to receive the enlarged connection between the rope 50 and the eye at the free end thereof. The rope 50 extends from the hook 425 along an arcuate groove 427 at the rear end of the turntable 107 so that such rope will be directed along the inner side of the machine as shown in Fig. 36. If desired, an anchorage may be located at 428 (Fig. 36) against the outer side of the machine while the friction clutch for the rope drum 208 is applied sufficiently to cause the rope 50 to effect a swinging feeding movement of the kerf cutter 46 from its full line position to its dotted line position while the cutter bits are being driven with the cutter bits arranged as shown in Fig. 3. Such operation as that illustrated in Fig. 36 may be performed on a steeply pitched vein with safety because during such operation the safety rope 51 may be anchored at 424 and the clutch for the rope drum 213 applied sufficiently to hold the rope 51 taut without effecting any longwall feeding movement. The safety rope 51 is then being relied on, however, to hold the machine in place and keep it from sliding down a steeply inclined mine bottom. 60

When the kerf-cutter is in its dotted line position shown in Fig. 36 the connection of the rope 75

50 to the cutter head is at 425' where it is accessible for detachment while the machine is close to the coal face.

The completion of the longwall cut of Fig. 35 is illustrated in Figs. 37, 38 and 39. The anchorage 429 for the safety rope 51 is changed from time to time as illustrated in Figs. 37, 38 and 39 and while such anchorage is fixed the anchorage for the feed rope 50 may be changed as desired to secure an arcuate feeding movement of the inner end of the kerf-cutter. During such operations an anchorage 430 may be located at the outer side of the machine as shown in Figs. 37, 38 and 39.

15 If at the upper end of the longwall kerf cutting operation, the mine bottom is substantially level the pin 41 in the recess locking mechanism for the cutter-head, may be released so that continued sliding of the machine over the mine bottom as illustrated in Figs. 40 and 41 will straighten out the cutter bar preparatory to the location of the machine for a sumping operation which may be performed as illustrated in Fig. 30.

As shown in Figs. 3 and 4 the ball bearing 57" 25 is mounted in a frame comprising a cap block 431 detachably mounted by means of the cap screws 432, 432. When the covers 65 and 116 (Fig. 1) are removed the cap 431 may be removed and the shaft 57 together with the parts connected thereto may be removed.

The plate 433 shown in Fig. 3 is detachably connected to the section 43 and when the plate 433 is unbolted the armature of the motor may be removed from the section 43. When the parts 35 are assembled as shown in Figs. 3 and 6 the motor and controller are safely enclosed in a flame-proof casing. However, when desired access to the commutator of the motor and the brushes associated therewith may be had by removing the 40 cover plates 434, 434 shown in Fig. 1.

The gearing is enclosed in the various chambers as shown in the accompanying drawings not only for the purpose of lubrication and the keeping of dust and foreign material therefrom but 45 also to render the machine as noiseless in operation as possible because it is important that the operation of the machine shall be sufficiently quiet not to drown out the warning signals given to the operators by the preliminary settling of the 50 roofs in the mine chamber prior to complete subsidence thereof. When the machine operates quietly such warning signals which are given when the roof starts to sag, enable the operators to move to places of safety until the subsidence 55 of the roof has occurred.

It should be particularly understood that the 60 flexibility of adjustments and operation of the machine illustrated in the accompanying drawings and the safety in operation along steep grades to cut kerfs in steeply pitched veins enables the machine to be operated not only in the longwall method of mining but also in the room and pillar and shortwall methods of mining. The machine is particularly adapted for operation 65 in very low roof mine veins but notwithstanding this fact the machine may be operated very efficiently because all of the controls except the emergency stopping means for the motor, are located at the feeding section or front end of the 70 machine, where such controls are located between the horizontal planes extending through the top and bottom of the machine. As may be seen by referring to Fig. 2 the radial handles 247 and 247' are well below the top plane of the 75 machine affording ample room for the hands of

the operator and a greater accuracy in the application of the clutches is obtainable by reason of the fact that the actuating wheels 246 and 246' are stationary during rotation of the rope drums. It is also worthy of note that the hydraulic jacks 5 may be controlled from the feeding section of the machine for varying the elevation of the kerf-cutter as hereinbefore explained.

As shown in Figs. 2 and 6 all of the feeding and haulage mechanism is located between the top and bottom planes of the machine and between the spaced apart vertical planes which extend through the sides of the cutter frame. The pawl and ratchet feeding mechanism shown in Fig. 6 comprises only a single vertical shaft 10 144 and the manual mechanism for operating the high speed or haulage clutch shown in Figs. 13 and 14, is permanently located inside of the adjacent vertical plane extending through the 15 side of the machine.

As shown in Fig. 7 the worm gear 143 is 20 detachably connected to the cam 146. A plurality of openings spaced circumferentially on the worm gear 143 may be provided so that the cam 146 may have a plurality of positions with respect to the worm gear 143. This arrangement enables the life of the worm gear 143 to be prolonged by adjustment thereof to a new position after wear or a maximum load. The pawl 175 is driving the ratchet wheel 162 in an anti-clockwise direction 25 as viewed in Fig. 6. In other words, the eccentric cam 146 is adjustably secured to the worm wheel 143 so that the relative positions of these parts may be varied to allow a plurality of separate places on the worm wheel in turn to be 30 placed in the position of maximum load and wear, thus securing the greatest possible wear from the worm wheel before replacement is necessary.

It should also be noted that only six gears in 35 all and a ratchet wheel are required to drive the two drums and attain numerous feeding speeds and a relatively fast haulage speed when the clutch of Figs. 13 and 14 is thrown in. In order to enable the use of rope drums each relatively 40 large in diameter while maintaining reduction in the width of the machine, these rope drums are 45 mounted with their vertical axes in a diagonal vertical plane as shown in Fig. 6. That is to say, the space ahead of the motor is utilized for the location of the rope drums and the feeding and 50 hauling mechanism connected thereto, and the rope drums are diagonally arranged within the lateral confines of the machine so that their diameters may be increased. The direction sheaves 233 and 248 also have their vertical axes within 55 the side limits of the machine so that their peripheries will be in positions to direct the ropes approximately in alinement with the sides of the machine when arranged as shown in Fig. 6.

It is preferable to rotate the spur gear 211 in 60 Fig. 8 approximately 10% faster than the spur gear 202 in order to assure the holding taut of the safety rope under average conditions of operation. Under some circumstances the convolutions of the feed rope on the rope drum 208 may 65 be greater than the convolutions of the safety rope on the rope drum 213 and consequently the effective diameter of the safety rope drum will be less than the effective diameter of the feed rope drum. The tendency under these 70 conditions is for the safety rope to become slack and if the feed rope should break or its anchorage become detached, the sliding of the machine by its own weight down an inclined mine bottom might effect a sudden jerk on the safety rope 75

and detach its anchorage. To overcome such tendency of the safety rope to become slack under the conditions referred to, the spur gear 211 is rotated 10% faster than the spur gear 202. During normal operation the friction clutch for the feed rope drum is fully applied while the friction clutch for the safety rope drum is applied only sufficiently to hold the safety rope taut during feeding movements of the machine. The feature of the 10% increase in relative speed of the safety rope drum and the slipping of the friction clutch applied to the safety rope drum, enable such regulations to be had that the safety rope will be held taut during all normal operations so that it will be effective immediately after the feed rope becomes slack, in co-operating with the pawl and ratchet mechanism shown in Figs. 6 and 10, to prevent retrograde movement of the machine down an incline.

20 The directional sheaves 248 and 232 shown in Figs. 1, 1^a and 2 for receiving the ropes 50, 51 direct from the rope drums are preferably tapered upwardly or provided with a conical surface to facilitate the winding of the ropes on the drums and the unwinding of the same therefrom during the various operations above described. Such tapering tends to keep the ropes up notwithstanding floor anchorages, thereby assuring proper winding of the ropes onto the rope drums.

30 The upper directional sheave 233 is preferably used for the feed rope 50 when arranged as illustrated in Fig. 34 or when arranged as illustrated in Fig. 36.

The term "Shortwall" used herein is the trade-mark of the Jeffrey Manufacturing Company, a corporation of Ohio, the assignee of this application, said trade-mark having been registered October 31, 1911, in Class 23, Cutlery, machinery, and tools, and parts thereof, registration No. 84,006, and renewed June 9, 1931.

Numerous features disclosed in this application are the sole invention of Lewis E. Mitchell and are disclosed and claimed in the application for a Mining machine, Serial No. 716,660, filed 45 March 21, 1934. These features include: the means for tilting and adjusting the mining machine, including the hydraulic operated skids; the removable gear mechanism for driving the cutter chain; the pivoted cutter bar mechanism and 50 the means for swinging said bar and for locking it; the particular guide sheave arrangement illustrated in Fig. 1a; the specific clutch operating mechanism for the friction clutches in which the operating lever is non-rotatably mounted; the 55 specific flame-proof motor and control construction; the specific motor control means illustrated in Fig. 27; the emergency motor control means operable from the rear end of the mining machine; and the specific cutting mechanism and 60 clutch mechanism for controlling said specific cutting mechanism.

Obviously those skilled in the art may make various changes in the details and arrangement of parts without departing from the spirit and 65 scope of the invention as defined by the claims hereto appended and we therefore wish not to be restricted to the precise construction herein disclosed.

Having thus described and shown an embodiment of our invention, what we desire to secure by Letters Patent of the United States is:

1. In a mining machine, the combination with a supporting frame, adapted to rest on and slide over a mine floor, of cutting mechanism mounted 70 on said frame, means for driving said cutting

mechanism, feeding mechanism comprising a power driven winding drum and a flexible draft element connected thereto and wound thereon, safety mechanism connected to said feeding mechanism and comprising an auxiliary power driven winding drum and a safety draft element connected thereto and wound thereon, said auxiliary winding drum being independent of said first-named draft element, a friction device connected to said auxiliary winding drum to control the latter to effect the holding of its flexible draft element taut while the free end of the latter is connected to a fixed anchorage in the mine and the free end of the first-named flexible draft element is anchored and a feeding pull exerted thereon by said first-named power driven winding drum, and safety mechanism to prevent unwinding of the second-named flexible draft element from the auxiliary winding element if the feeding draft element should break or its anchorage become detached.

2. In a mining machine, the combination with a supporting frame, of cutting mechanism therefor, means for driving said cutting mechanism, feeding mechanism comprising a rope drum and a feed rope extending therefrom, a safety rope drum, a safety rope connected to said safety rope drum and adapted to be extended approximately its full length therefrom to an anchorage in the mine, means for rotating said rope drums to wind up said ropes thereon simultaneously, said rope drums being geared together independently of said ropes to rotate in opposite directions with the safety rope drum rotating at a higher speed than the feed rope drum to keep the safety rope taut while the free end of the feed rope is connected to an anchorage nearer the machine than the anchorage to which the free end of the safety rope is connected, and pawl and ratchet mechanism associated with the safety rope drum to prevent reverse rotation thereof and to prevent retrograde movement of the mining machine down an incline in the event of the feed rope becoming inoperative to prevent such retrograde movement, and means for controlling the application of power to said rope drums to secure feeding pull on the feed rope and only sufficient pull on said safety rope to keep the same taut during feeding movement of the cutting mechanism so that said safety rope will be maintained in readiness to act as a safety rope when the aforesaid emergency is encountered.

3. In a mining machine, the combination with a supporting frame, of cutting mechanism thereon, means for driving said cutting mechanism, adjustable unidirectional feeding means for the cutting mechanism, and means comprising a releasable spring loaded clutch for effecting a relatively fast haulage movement of the entire machine without interference from said feeding means, said clutch including means operative to render said fast haulage means ineffective if driven in the wrong direction.

4. In a mining machine, the combination with a supporting frame adapted to rest on and slide over a mine floor, of cutting mechanism mounted thereon, means for driving said cutting mechanism, driving elements geared together, motor operated mechanism for rotating said driving elements at different feeding speeds, two winding drums one mounted on each of said driving elements to rotate on the axis thereof, means preventing reverse rotation of one of said drums, two separate and independent friction clutches

- one for each of said winding drums to connect said driving elements to said winding drums, flexible draft elements wound on and extending from said winding drums to fixed anchorages in the mine, and means for actuating said clutches independently of each other to cause either winding drum to wind in its flexible draft element while the other winding drum pays out its flexible draft element thereby enabling the machine to perform shortwall operations along a mine face in either of opposite directions, or to cause one drum to wind in to perform a longwall operation while the other drum acts as a safety device.
5. In a mining machine, the combination with a main haulage and feeding means comprising a power actuated flexible draft element, of auxiliary haulage and feeding means comprising an additional power actuated flexible draft element, each draft element being free from any direct connection with the haulage and feeding means connected to the other draft element, and means associated with the auxiliary haulage and feeding means to prevent reverse movement of the machine in the event of failure of the main haulage and feeding means.
6. In a mining machine, the combination with a supporting frame, of mining mechanism mounted thereon, a main haulage drum, a second haulage drum geared to rotate in an opposite direction to that of the main haulage drum, a flexible draft element extending from the main haulage drum, a second flexible draft element extending from the second haulage drum independently of the main haulage drum, means for operating said haulage drums for either feeding or hauling the machine, and means associated with the second haulage drum to cause the flexible draft element extending therefrom to act as a safety device to prevent reverse movement of the machine.
7. In a mining machine, the combination with a supporting frame, of cutting mechanism carried thereby, means for driving said cutting mechanism, feeding mechanism comprising a rope drum and a rope extending therefrom for connection to an anchorage in the mine, an auxiliary rope drum, a rope extending from said auxiliary rope drum for connection to another anchorage in the mine, means for rotating said rope drums simultaneously each to exert a feeding pull on its rope, and means additional to said feeding mechanism and said rope drums to prevent reverse rotation of the auxiliary rope drum if the first-named rope should break or its anchorage become detached.
8. In a mining machine, the combination with a supporting frame, of cutting mechanism carried thereby, means for driving said cutting mechanism, feeding means comprising a rope drum and a rope extending therefrom for connection to an anchorage in the mine, an auxiliary rope drum, a rope extending from said auxiliary rope drum for connection to another anchorage in the mine, means for rotating said auxiliary rope drum from said feeding mechanism to exert a feeding pull on the rope extending from the auxiliary rope drum, and pawl and ratchet mechanism associated with said auxiliary rope drum to prevent unwinding rotation thereof if the first-named rope should break or its anchorage become detached and the machine tends to move down an incline of its own weight in a direction opposite to the direction of feeding movement of the machine.
9. In a mining machine, the combination with a supporting frame, of cutting mechanism mount-
- ed thereon, means for driving said cutting mechanism, a plurality of haulage rope drums, a plurality of flexible elements one connected to and wound on each rope drum with its free end adapted to be connected to an anchorage in the mine, means for rotating each of said rope drums in a direction to exert a pull on its rope when its free end is anchored, clutches one for each of said rope drums to secure independent control thereof, and pawl and ratchet mechanism associated with one of said rope drums to prevent unwinding rotation thereof.
10. In a mining machine, the combination with a supporting frame adapted to rest on and slide over a mine floor, of cutting mechanism thereon, means for driving said cutting mechanism, a feeding winding drum mounted on said frame to rotate on a vertical axis with its periphery moving at one side of the machine toward the cutting mechanism, a feeding winding drum mounted to rotate on said frame on a vertical axis with its periphery movable along the other side of the machine toward said cutting mechanism, flexible draft elements extending from said drums to fixed anchorages in the mine, driving mechanism comprising separate and independent friction clutches for said drums to effect rotation of the latter in opposite directions with their peripheries at the sides of the machine movable toward said cutting mechanism, and safety mechanism to prevent paying out of the draft element from one of said drums when the machine tends to slide down a steep grade in the mine.
11. In a mining machine, the combination with a supporting frame, of a kerf-cutter mounted thereon, feeding and safety mechanism comprising two winding drums mounted upon spaced-apart vertical axes and having flexible draft elements extending to anchorages in the mine, the safety rope drum being geared to the feeding rope drum to rotate faster than the latter, and power transmission means between said motor and the feeding rope drum to rotate the latter and cause transmission to said safety rope drum, both of said rope drums being rotated in winding directions with the safety rope drum rotating faster than the feeding rope drum.
12. In a mining machine, the combination with a supporting frame, a stationary vertical bearing on said frame, a cylindrical screw-threaded support secured to the upper end of said bearing, an internally threaded thrust collar mounted on said support for reciprocation therealong, a rope drum, means comprising ball-bearings for suspending said rope drum from said thrust collar, a clutch element journaled on said bearing, a thrust ball-bearing between said clutch element and said support, a second clutch element mounted on said rope drum and journaled on said first-named clutch element, and radial handles on said thrust collar for rotating the same and effecting the application of said clutch elements.
13. In a mining machine, the combination with a supporting frame, of cutting mechanism therefor, means for driving said cutting mechanism, feeding mechanism comprising a feed rope drum and a feed rope extending therefrom, a safety rope drum, a safety rope connected to said safety rope drum and adapted to be extended therefrom to an anchorage in a mine, motor means for rotating said rope drums to wind up said ropes thereon simultaneously, said means tending to drive said drums at approximately, but not exactly, the same speeds, with the safety drum tending to rotate at a higher speed, means allow-

ing slippage between the safety drum and the driving means, whereby the safety rope will always be taut but will not feed the machine while the feed rope performs the feeding function, and 5 pawl and ratchet mechanism associated with the safety rope drum to prevent reverse rotation thereof thereby to prevent retrograde movement of the mining machine down an incline in the event of the feed rope becoming inoperative to 10 prevent such retrograde movement.

14. In a mining machine, the combination with 15 a supporting frame, of a kerf-cutter mounted thereon, feeding and safety mechanism comprising a safety drum and a feeding drum having flexible draft elements extending to anchorages in the mine, driving means adapted to drive said safety drum faster than said feeding drum, clutch 20 means providing slippage between said driving means and said safety drum whereby the feeding drum will perform the feeding operation while the safety drum draft element is maintained taut without performing any appreciable feeding operation, and means for preventing reverse movement of said safety drum.

15. In a mining machine, the combination with 25 a supporting frame, of a kerf-cutter mounted thereon, feeding and safety mechanism comprising a safety drum and a feeding drum having flexible draft elements extending to anchorages in the mine, driving means adapted to drive said safety drum faster than said feeding drum, clutch 30 means providing slippage between said driving

means and said safety drum whereby the feeding drum will perform the feeding operation while the safety drum draft element is maintained taut without performing any appreciable feeding operation.

5

16. In a mining machine, the combination with a body including a frame plate, of a motor-driven drive shaft, a drum driven by said shaft, the lower face of said drum being positioned near said plate, and rotating means adapted to prevent an 10 accumulation of dirt on said plate beneath said drum, said means comprising a star-shaped plate positioned between said drum and said plate.

17. In a mining machine, the combination with a body including a frame plate, of a motor-driven 15 drive shaft, a drum driven by said shaft, the lower face of said drum being positioned near said plate, and rotating means adapted to prevent an accumulation of dirt on said plate beneath said drum, said means comprising a rotating member 20 having projecting cam portions adapted to force dirt outwardly thereof when rotated.

18. In a mining machine, the combination with a body including a frame plate, of a motor-driven 25 drive shaft, a drum driven by said shaft, the lower face of said drum being positioned near said plate, and rotating means adapted to prevent an accumulation of dirt on said plate beneath said drum.
